C. E. FAIRBANKS.
QUANTITY STOP FOR DISPENSING PUMPS.
APPLICATION FILED OCT. 25, 1915.

1,191,882

Patented July 18, 1916.

UNITED STATES PATENT OFFICE.

CHARLES E. FAIRBANKS, OF WEST SPRINGFIELD, MASSACHUSETTS, ASSIGNOR TO
GILBERT & BARKER MANUFACTURING COMPANY, OF WEST SPRINGFIELD, MASSA-
CHUSETTS, A CORPORATION OF MASSACHUSETTS.

QUANTITY-STOP FOR DISPENSING-PUMPS.

1,191,882.

Specification of Letters Patent. Patented July 18, 1916.

Application filed October 25, 1915. Serial No. 57,713.

To all whom it may concern:

Be it known that I, CHARLES E. FAIRBANKS, a citizen of the United States of America, and residing in West Springfield, in the county of Hampden and State of Massachusetts, have invented certain new and useful Improvements in Quantity-Stops for Dispensing-Pumps, of which the following is a specification.

10 This invention relates to improvements in quantity stops for measuring pumps, such as are commonly used in dispensing gasoline and like oils.

More particularly, it relates to improved construction in the quantity stop itself, as distinguished from the system and arrangement of stops for co-operative action with the pump, and the individual stops are adapted to be used and arranged in a manner similar 20 to that shown in the patent to J. B. Davis, No. 874,574, granted December 24, 1907.

An object of the invention is to provide an improved quantity stop which is arranged for convenient and accurate adjustment on 25 its supporting rod.

Another object of the invention is to provide in a quantity stop construction simple and improved means for sealing the stop in its adjusted position.

30 Another object is to provide an improved quantity stop construction which is characterized by extremely simple and generally improved mechanical structure.

Further objects and advantages will appear in the detailed description and annexed 35 claims.

Referring to the drawings as illustrating one preferred manner in which the invention may be put to use Figure 1 is a general 40 elevational view of a dispensing pump illustrative of the arrangement of the quantity stops therein; Fig. 2 is an elevational view on an enlarged scale of the quantity stops and the supporting means therefor; Fig. 3 45 is a sectional plan view taken on the line 3—3 of Fig. 2 and looking in the direction of the arrows; Fig. 4 is a front elevational view of a portion of Fig. 3; Fig. 5 is a plan view of a single quantity stop; and Fig. 6 50 is a sectional elevation taken on the line 6—6 of Fig. 5 and looking in the direction of the arrows.

Referring to these drawings in detail, A represents the lower casing of a well known

form of dispensing pump, and B represents 55 doors which inclose the upper part of the pump. This type of pump, as is generally well understood, operates by means of a rack *a* which is connected to the pump piston and may be reciprocated by a handle *b* through suitable gearing. The outlet of the 60 pump is indicated generally at *c*. Mounted in parallel relation to and adjacent the rack *a* is a rotatable rod 1 which is threaded 65 throughout the greater portion of its length as clearly shown in Fig. 2. Secured on this rod in a manner to be described are quantity 70 stops 2, any one of which may be swung into the path of a projection 3 on the rack *a*, whereby the extent of movement of the latter may be limited. These stops 2 are angularly spaced one from another, as clearly 75 shown in Fig. 3, and are movable by a lever 4 fixed to rod 1. The lever moves closely adjacent a sector plate 5 which has suitable 80 notches 6 to engage a depending projection 7 on the lever, as clearly shown in Figs. 3 and 4. The plate 5 is preferably graduated to indicate visually to the operator which 85 stop 2 lies in the path of projection 3, and these graduations may, for example, be arranged to indicate a pint, quart, and half gallon, etc. These stops co-operate with the projection 3 in a manner well known in the art to measure quantities delivered from the 90 pump.

The general operation of the pump is well known and the general arrangement of the quantity stops just described is disclosed in the above-mentioned patent. This invention 95 is concerned particularly with an improved construction of the quantity stop itself for use in a pump of the type described.

The construction of the stops 2 is best shown in Figs. 5 and 6, and one thereof will 95 be described with particular reference to these figures. The stop 2 comprises a hub portion 10 and a laterally outstanding ledge 11 which is formed with horizontally spaced and vertically inclined wings 12. The hub 100 portion 10 has a smooth vertical bore therein to loosely slip over the threaded rod 1. Above and below the hub portion 10 are check nuts 13 which engage the threads on rod 1 and permit vertical adjustment of the 105 stop 2 thereon. The outstanding portion 11 has a lower surface 14, which is arranged to engage the projection 3 on the rack *a*, and

on its upper portion is a recess formed by and between the spaced inclined wings 12. A horizontally disposed set screw 15 passes through the hub portion 10 to hold the latter firmly to the rod irrespective of the nuts 13, and this set screw leads to and is applied from the recess in the upper part of the ledge 11 just described. After the set screw 15 has been applied an angularly shaped block 16 is laid into the recess to conceal the set screw. The blocks 16 and wings 12 have registering holes, as indicated in Figs. 5 and 6 to permit a wire 17 to be passed therethrough, and the ends of this wire may be sealed as indicated at 18, whereby access to the set screw is prevented. Each of the check nuts 13 also have several holes therein, as shown in Figs. 3 and 6, whereby the two may be connected by a wire 19, and the latter sealed as shown at 20 on the upper stop in Fig. 2. Preferably, however, a single wire 21 is passed through the holes in the wings 12, block 16, and both nuts 13, as shown in connection with the lowermost stop in Fig. 2, and a single seal 22 is thus sufficient for each stop.

The quantity stop 2 has several advantageous features which result from the construction just described. It is, first of all, very simple in structure and consequently desirable in practice on the score of low cost of manufacture. The stop itself, involving the portions 10, 11, and 12, is a one-piece structure, which may conveniently be formed at a single operation. It may be cast if desired but is preferably made by drop forging and, when made in either manner, requires little finishing. It is necessary only to bore the central hole in the portion 10, the small holes in the wings 12, and to drill and tap the hole for the set screw 15. Likewise, the block 16 needs no accurate finishing and requires simply the drilling of a small hole for the sealing wire 17. The check nuts 13 and set screw 15 are standard parts which may be bought at a low price. However, although the structure is simple and cheap to produce, it provides for accurate and convenient adjustment as well as for means to seal the parts in adjusted position. Before the screw 15 is set in place, the stop is held between a pair of check nuts and, by manipulating the latter, the stop may be moved up and down by as small increments as desired to obtain an accurate vertical positioning of the stop 2. Having adjusted the latter vertically on the rod 1, the stop may be swung on the rod without altering its vertical position to obtain the necessary angular adjustment. Thereafter, the screw 15 is jammed into the rod 1 to preserve both the vertical and angular adjustments, and both may be simply and conveniently sealed as already described. It is to be noted that, whereas continued en-

gagement of the stop with the projection 3 on the rack might well dislodge the stop on the rod if the screw 15 were alone relied upon to hold the stop to the rod, such engagement when indefinitely continued does not affect the accurately adjusted position of the stop 2 on the rod 1 with the construction described because the stop is backed up by a check nut 13. This feature is advantageous in practice because it maintains the accurate adjustment of the stop in spite of careless and heedless operation of the pump and particularly because a dislocation of the stop, as described, would cause the pump to overmeasure. Thus, an improved quantity stop has been provided which is simple, inexpensive to manufacture, and may be accurately adjusted and sealed.

It is recognized that various modifications may be made in the structure herein described for illustrative purposes without departing from the scope of the invention which is defined by the appended claims rather than by the foregoing description.

What I claim is:—

1. In a measuring pump, a supporting frame, a reciprocable bar for operating the pump having a projection thereon, a threaded rod rotatably mounted in said frame in parallel relation to said bar, a plurality of stop devices loosely engaging said rod, nuts threaded on said rod above and below each stop, whereby the stops may be vertically moved for adjustment, a set screw in each stop engaging said rod whereby the stops may be held in various positions of angular adjustment and the vertical adjustment preserved, irrespective of said nuts, means to seal said set screws, said stops arranged in angular relation one from another on the rod, and means to rotate said rod to swing any one of said stops into the path of said projection.

2. In a measuring pump, a reciprocable pump operating bar having an abutment thereon, a rotatable threaded rod in parallel relation to said bar, a plurality of vertically spaced stop devices arranged in angular relation one to another on said rod, and means to turn the latter through definite angular increments to bring each stop device successively into the path of said abutment, each stop device comprising a hub portion loosely mounted on the rod, a ledge laterally extending from the hub portion to contact with the abutment, integral spaced wings connecting the ledge and hub portion, threaded members on the rod above and below the hub portion whereby the latter may be vertically moved and accurately adjusted, said hub portion being freely revolvable on the rod without disturbing said vertical adjustment, securing means to hold the hub portion to the rod after the former has been angularly adjusted, said means being ap-

plied above the ledge and between the wings, a device constructed to fit between the latter and prevent access to the securing means, and sealable means to hold said device in position, all constructed and arranged so that each stop may be accurately adjusted vertically and angularly on the rod and thereafter sealed in its adjusted position.

3. In a measuring pump, a reciprocable operating bar for the pump having an abutment thereon, a rotatable threaded rod parallel with the bar, a plurality of vertically spaced stop devices arranged in angular relation one to another on said rod and means to turn the latter through definite angles to swing any one of the stops into the path of the abutment, each of said stops comprising

a hub portion slidable on said rod, check nuts above and below the hub portion, whereby the latter may be moved and accurately adjusted vertically on the rod, a laterally outstanding ledge integral with the hub portion and adapted to engage said abutment, said ledge having upright spaced wings, a set screw applied to the hub portion above said ledge and between said wings to hold the stop in the desired position of angular adjustment on the rod, a block arranged to fit between said wings and lie upon said ledge to conceal the set screw and prevent access thereto, and sealable means to hold the block in position, as described.

CHARLES E. FAIRBANKS.
